W. J. KEEP & C. WIPFLER.

HEATING STOVE.

No. 16,818.

Patented July 27, 1886.

UNITED STATES PATENT OFFICE.

WILLIAM J. KEEP AND CHARLES WIPFLER, OF DETROIT, MICHIGAN.

DESIGN FOR A HEATING-STOVE.

SPECIFICATION forming part of Design No. 16,818, dated July 27, 1886.

Application filed May 10, 1886. Serial No. 201,751. Term of patent 7 years.

To all whom it may concern:

Be it known that we, WILLIAM J. KEEP and CHARLES WIPFLER, of Detroit, in the county Wayne and State of Michigan, have invented 5 new and useful Improvements in Design for a Heating-Stove and its Several Parts; and we do hereby declare that the following is a full, clear, and exact description thereof, reference being had to the accompanying drawings, 10 which form a part of this specification.

This invention relates to a certain new and original design for a heating-stove and its several parts, as shown in the accompanying photographic illustration, forming a part of 15 this specification.

A is the leg, of the curved outline as shown, the lower part of which, upon its front face, is principally smooth, with a small central ornamentation, as shown, and a beading 20 rounding its edge, which is curved upon itself, as shown, at the lower extremity of the leg. The upper part of this leg is of the shape shown, with its front face subdivided into diamond-shaped ornamentation by transverse lines or grooves nearly parallel to each 25 other.

B is a screen below the bottom proper, of suitable length, when in place, to form an ornamental connection between the legs situated 30 at each corner of the base of the stove. This screen is of the shape and outline shown, being straight along its upper edge, serpentine along its lower edge, and semicircular at each end. Its ornamentation consists of a rosette 35 at each end, with four intermediate and smaller rosettes. Each end rosette and the nearest two intermediate rosettes are inclosed in ornamental scroll-work, as shown.

C is the base proper of the stove. It consists of a plain and nearly-vertical band, the 40 upper edge of which is rounded off to form a graceful connection with a parallel riser, which curves inwardly to the junction of its upper edge with the bottom plate of the ash- 45 pit section.

D is one of the vertical sides of the ash-pit section of the stove. It is rectangular, and its ornamentation consists of a central rosette, representing a flame emanating from a central 50 fire, and surrounded by scroll-work and palm-points, which nearly cover the presented face of the plate, as shown.

E is the door of the ash-pit section. Its form is rectangular, and its ornamentation consists of a larger rosette of raised panel-work near 55 each lower corner, with a row of three smaller rosettes, each inclosed in a shell, equidistant from each other, and arranged just below the upper edge of the door, while the spaces not filled by the rosettes are ornamented by 60 scroll-work, as shown.

F is a foot rest or rail for the sides of the ash-pit section of the stove. It consists of a pair of brackets, one at each end of the rail, as shown, the lower ends of said brackets resting 65 against the base-section, while the upper ends rest against the upper end of the ash-pit section, at which point the upper ends of the brackets are connected by a curved and corrugated plate, presenting, when in place, 70 the appearance of a rounded corrugated rod. Nearly midway between the ends of the brackets is the rail proper, presenting an outwardly-sloping foot-rest, the front face of which is ornamented with scroll-work terminating in a 75 serrated edge at the highest point of the rail. The front faces of the brackets are ornamented with scroll-work of what is generally called the "shell pattern," as shown. The brackets, rod, and rail are preferably cast integral 80 with each other.

G is the foot rest or rail for the front of the stove. It consists of two brackets, such as have already been described in connection with the foot-rest F, and ornamented in the 85 same manner, but without the top connecting bar or plate. The rail itself connects the two brackets, as in the figure F, the front presenting a sunken panel, in which is presented, in raised letters, the trade-name given to the 90 stove, the upper edge of the rest being serpentine and its front ornamented with a scroll-fret, as shown.

H is the upper part of the ash-pit section of the stove, whereby a pleasing conjunction is 95 made between the upper end of the vertical portion of the ash-pit section and the smaller fire-pot section above it. The lower edges of the plates forming the front part of this part of the ash-pit section consist of an imitation 100 roll, the presented face of which is ornamented with converging and diverging lines of scroll or corrugated work, as shown, and above this the plate recedes in two successive steps, and

terminates in a rearwardly and upwardly projecting face, which is ornamented in panel-work, as shown.

1 is the fire-pot section, superimposed upon 5 the ash-pit section. It consists of mica doors, as shown.

J is the combustion-chamber, and it also consists of mica doors, as shown, the architectural design of the doors and that of the 10 fire-pot section being of a similar character.

K is the top plate of the combustion-chamber section. It consists of a plain vertical band slightly rounded in its front presentation, and from this there rises an inwardly and up- 15 wardly curved face, which is corrugated, as shown.

L represents the front plate of the magazine section or feeder section of the stove. It consists of a plate with a "flare" or outward curve near its upper edge. Its ornamentation consists of a central rosette resembling flames radiating from a central point, with two rosettes of a different character, as shown, on the right and left of the central 25 rosette, the blank spaces around such rosettes being filled with scroll and "lance" work, while the representation of creeping flames is seen at each end of the plate near the corners of the stove.

30 M is the side plate of the feed-section, and in its form, configuration, and ornamentation is precisely like the plate L, except that this plate M has but a central rosette, with one rosette at the right and left of the central one, as shown.

N is the top of the magazine-section. It consists of a rectangular plate with rounded corners, and a central orifice covered by the cap O. This plate has an overhanging beveled edge, which is plain. From the upper edge of the beveled part rises the convex surface of the top, which is ornamented with a rosette near each corner, the spaces between which are filled in with scroll-work, as shown.

45 O represents the cap over the magazine-section of the stove. It consists of a convex or inverted saucer shape, with a plain beveled band surrounding its lower edge, the balance of the presented surface being ornamented by 50 rosettes and scroll-work, as shown.

P is the representation of an ancient warrior standing in a proper position for attack and defense, and with his shield presented

against attack. The head of the figure is covered by a helmet, and the figure stands upon a pedestal, which is secured to the top of the cap.

What we claim as our invention is—

1. In a design for a stove, the screen B, of the form and configuration shown, and ornamented with a rosette at each end and four intermediate rosettes, as shown and described. 60

2. In a design for a stove, the plate D, ornamented with a rosette representing a flame emanating from a central fire, as shown. 65

3. In a design for a stove, the ash-pit door E, ornamented with a plurality of rosettes, each inclosed in a shell, as shown.

4. In a design for a stove, the rail F, ornamented with a rosette, and its supporting brackets, the whole forming the foot-rest of a stove, as shown and described. 70

5. In a design for a stove, the front plate, L, of the magazine-section, ornamented with a central rosette and two rosettes of a different character on opposite sides thereof, as shown. 75

6. In a design for a stove, the plate M, ornamented with a central rosette and a single rosette upon each side thereof, as shown.

7. In a design for a stove, the cap O, ornamented with rosettes and scroll-work, said rosettes being within the scrolls, as shown and described. 80

8. In a design for a stove, the plate N, which forms the top of the magazine of the stove, having rounded corners and an overhanging beveled plain edge, and ornamented with rosettes and scroll-work, said rosettes being within the scrolls, as shown. 85

9. In a design for a stove, the cap O, ornamented with rosettes and surmounted by the figure P, standing upon a pedestal on the top of the cap, as shown and described. 90

10. In a design for a stove, the legs A, screens B, base C, plate D, ash-pit with door E, rails F G, upper part, H, of ash-pit, fire-pot and combustion-chamber sections, top K, plates L M, top N of the combustion-chamber, and cap O, of the form, outline, configuration, and ornamentation shown and described. 95
